RESISTANCE CONDUCTOR

William Alleva, Jenkintown, and Herbert Blackburn, Yeadon, Pa., assignors to I-T-E Circuit Breaker Company, Philadelphia, Pa., a corporation of Pennsylvania

Application December 14, 1944, Serial No. 568,192

1 Claim. (Cl. 201—63)

1

Our present invention relates to resistors of the type wound on a ceramic tube and having metallic ferrule terminals. More specifically, our invention relates to the means for mounting the metallic ferrules on the ends of a ceramic tube in such manner that they will not be dislodged during or after any firing or other heat treating processes to form a vitreous coating on the outside of the wound resistance wire.

Our invention contemplates metallic ferrule cups having a series of indentations or dimples on the periphery thereof whereby the cups may be forced over the ends of the ceramic resistor form or tube so that the tension of the indentations or dimples pressing against the outside of the ceramic tube is sufficient to keep the ferrule cup tightly in place. These indentations or dimples are sufficient to keep the ferrule from loosening while the whole resistor unit is subject to the high temperatures required for firing or baking of a vitreous enamel insulating coating thereover.

For many years after the advent of the ferrule type resistor, it was common practice to affix the ferrules only after the firing or heat treating process had occurred; this was accomplished by the use of metal slugs cemented inside the ceramic form, or by the use of a screw bolt. Any attempt to fasten the ferrules to the ceramic tube before the firing process resulted in failure, owing to the fact that the difference in expansion between the ceramic material and the metallic ferrule material was so great that the ferrules invariably loosened under the customary high firing temperatures.

One departure from the foregoing methods was that of utilizing a ferrule of metallic material having a relatively low coefficient of expansion, together with a shim or insert of special design made of a soft metal with a higher coefficient of expansion than the ferrule. This shim or insert was placed inside the ferrule and the whole was forced over the outside of the ceramic tube which resulted in the shim or insert taking up the excess space between the inside wall of the ferrule and the outside wall of the tube. Thus on a rise in temperature, the shim expanded more than the ferrule cup and thereby kept the ferrule tight on the ceramic material which was negligible expansion.

Our invention contemplates a further and novel step which dispenses entirely with any shim or insert and thus decreases the number of operations necessary in the manufacture of the resistor while, nevertheless, retaining all the advantages

2

of a tight ferrule on the ceramic tube during all of the operations. Our invention also makes possible the formation of a transverse hole through the entire length of the resistor open to the free air to aid in heat dissipation.

A primary object of our invention, therefore, is the provision of novel simplified means for securing a metallic ferrule cup to a ceramic resistor form in such manner that the ferrule will not be dislodged during baking, firing, or other heat treating processes.

Another object of our invention is the formation of the ferrule so that the securing means are integral with the ferrule and need not be separately handled in any way.

Still another object is the formation of the integral securing means for the ferrule in a simplified easily produced, easily handled manner.

Still a further object of our invention is the formation of tensioning means integral with the metallic ferrule cup in order at all times to maintain the mounting of the metallic ferrule cup on the resistor form irrespective of the temperature to which the said resistor form is subjected.

25 A specific object of our invention is the formation of indentations or dimples at spaced portions of the periphery of the ferrule in order to enable the same to grip the sides of the ceramic resistor form at all times irrespective of the temperature to which the entire unit is subjected.

Another object is the provision of simple wire connecting means for the ferrule.

These and many other objects of our invention will become apparent from the following description and drawings in which:

Figure 1 is a view in perspective of a hollow ceramic resistor form with the metallic ferrule cup mounted thereon.

Figure 2 is a cross-sectional view taken on line 40 2—2 of Figure 5.

Figures 3 and 4 are side views of metallic ferrule cups showing slightly modified indentations or tensioning means thereon.

Figure 5 is a view in perspective showing a novel 45 connector for the ferrule.

Referring now to Figure 1, we have here shown a hollow tubular resistor form 10 of ceramic material having the through opening 11. Metallic ferrule cups 15, 15 at each end each have opening 50 16 which registers with the opening 11 of the tube 10 when the ferrules 15 are mounted over the end of the tube 10. Each ferrule 15 has an annular end flange 18 which defines the opening 16 and bears against the end 19 of the tube thus 55 limiting and determining the position of the me-

tallic ferrule cup with respect to the tube 10. Each ferrule 15 also has a cylindrical side wall 20, the inside diameter of which is very slightly larger than the outside diameter of the tube 10. The cylindrical wall 20 of each of the ferrules 15 has a flared annular flange 21, the slight flare 22 of which facilitates the pushing of the metallic ferrule cup 15 over the end of the tube 10. The flange 21 has a re-entrant lip 25 in order to provide a finished appearance and construction.

The entire flange 21 with its reentrant lip 25 is provided with a pair of spaced cuts 27, 28, as shown in Figure 1, which provide a ready means of securing for the resistance wire. Thus, when the resistance is wound on the form 10, one end of the resistance is caught at the cuts or mounting means 27, 28 by being secured thereto in any suitable manner as, for instance, by being twisted around the material 29 between the cuts or openings 27, 28; the wire is then wound on the form 10 until it reaches the opposite ferrule and the opposite end of the resistor wire is secured thereto in the same manner.

The cylindrical wall 20 or periphery of the ferrule 15 is provided with a series of part spherical indentations 30, 30 (Figure 1). The circle defined by the interior surfaces of these indentations is essentially of less circumference than the outside circumference of the ceramic tube 10. However, the metallic ferrule cup (which is preferably made of Monel metal) is sufficiently elastic so that the said cup may be forced over the end of tube 10, and be slightly expanded by reason of the pressure of the indentations 30 against the outer surface of the tube 10.

We have found that after the resistance wire has been wound on the resistor form 10 and a suitable vitreous enamel coating applied thereto, and the entire unit subjected to baking, firing or other heat treating processes, that the metallic ferrule cup 15 nevertheless maintains its predetermined position with respect to the ceramic tube 10, has no movement whatever with respect thereto, does not become loosened with respect thereto at any time during the heat treating process or thereafter, and at all times is securely integrated with the ceramic tube 10.

Since the material of the metallic ferrule cup 15 is elastically distorted by reason of the pressure of the indentations against the sides of the ceramic tube 10 when the metallic ferrule cup 15 is forced thereon, any expansion of the metallic ferrule cup during the heat treating process is compensated for by the tendency of the material of the metallic ferrule cup 15 to return to its original undistorted position. Consequently, the indentations 30 need only be deep enough to compensate for the expansion of the material of the metallic ferrule cup 15. They may be slightly deeper in order to ensure a perfect grip at all times. The essential element is that the indentations 30 be sufficiently deep so that irrespective of the amount of expansion which may normally be expected of the material of the metallic ferrule cup 15, the circle defined by the interior surfaces of the indentations will not be greater in diameter than the outside diameter of the tube 10.

The elasticity of the metal of the ferrule cup 15, tending to restore the cup to its initial undistorted position will compensate for the expansion of the material. Where distortion has been mentioned in the foregoing, it does not mean that the ferrule cup is twisted or misshapen when mounted on the unit. The dis-

tortion referred to is only the initial give or very slight change in the diameter of the cylindrical wall 20 when the metallic ferrule cup 15 is forced over the end of the tube 10. Since the ceramic tube 10 has substantially no expansion at all under heat treating processes and the material of the metallic ferrule cup 15 may have a substantial coefficient of expansion, the difference between the coefficients of expansion is relatively large. However, the absolute amount of expansion of the metallic ferrule cup 15, while it is sufficient to loosen the metallic ferrule cup when it is expanded by heat, is nevertheless very small, and the indentations 30 which are provided compensate for this expansion. The distortion of the wall 20 of the ferrule 15 when it is placed over the end of the tube 10 is very small, is not visible to the eye, and does not affect the useful dimensions thereof.

It will be obvious that the indentations 30, instead of being part spherical, as shown in Figure 1, may have any appropriate shape which will accomplish the same purpose. Thus, as shown in Figure 3, the indentations 130 may be longitudinal rectangular indentations where the wall of the indentation defines a portion of a cylinder. As shown in Figure 4, the indentation 230 may be in the form of two intersecting substantially rectangular indentations which will afford an even better grip. Other forms of indentations may be used.

All of the foregoing holding means which are integral with the ferrule cup 15 and which may be used separately or in combination have as their common function, the defining of a circle by their interior surfaces, the circumference of which circle is less than the outer diameter of the tube 10 so that the material in the ferrule cup 15 will be elastically distorted to a slight extent when the ferrule cup 15 is forced over the end of the tube 10. This will create an elastic force tending to compress the wall of the ferrule 15, which elastic compressive force will compensate for and counteract the expansion of the material of the metallic ferrule cup 15 when the entire unit is subjected to baking, firing or other heat treating processes.

In Figures 5 and 2, we have shown a slight modification of our ferrule which will simplify the connection between the resistance wire and the ferrule. In these figures, the flange 21' of the ferrule 15' has no slits for wire fastening. Instead, a very thin (of the order of 38 gauge) strip 40 of copper having a reentrant flange 41 and notches 42 in its end 43 is used. The strip 40 is placed on the end of the tube 10' so that flange 41 bears against end 11' of tube 10' and the bcdy of the strip bears against the side of the tube. The ferrule 15' is forced on holding the strip 40 in place and making electrical contact therewith. The resistance wire may now be wound around notches 42 in end 43 of the strip 40.

It will be obvious therefore that our invention may be embodied in many modifications and variations which should now be obvious to those skilled in the art. Accordingly, therefore, we prefer to be bound not by the specific disclosures herein, but only by the appended claim.

We claim:

In combination, a ferrule and a resistor, said resistor having a ceramic tube, said ferrule being arranged to fit over the end of said tube; said ferrule having a cylindrical wall of a diameter slightly less than the outer diameter of said tube;

said wall having indentations, said indentations forming convex areas on the interior wall of said cylindrical wall, the circle defined by the interior surfaces of said indentations being of slightly less circumference than the outer diameter of said tube; said ferrule being made of electrically conductive elastic material sufficient to permit said ferrule to be forced over and be gripped by the end of said tube and sufficient so that irrespective of the amount of expansion which normally occurs to said metallic ferrule, the circle defined by the interior surface of said indentations will not be greater than the outside diameter of said tube; and a conductive strip; said strip being held in position by said ferrule; said strip comprising means for effecting a conductive connection to a wire.
